CLAIM

The ornamental design for a transcutaneous electrical_nerve stimulation (TENS) unit, as shown and described.

DESCRIPTION

FIG. 1 is a perspective view of an ornamental design for a transcutaneous electrical_nerve stimulation (TENS) unit showing my new design;

FIG. 2 is a front view of the TENS unit;

FIG. 3 is a rear view of the TENS unit;

FIG. 4 is a left side view of the TENS unit;

FIG. 5 is a right side view of the TENS unit;

FIG. 6 is a top view of the TENS unit; and,

FIG. 7 is a bottom view of the TENS unit.

The broken lines in the drawings depict portions of the transcutaneous electrical nerve stimulation (TENS) unit that form no part of the claimed design.

1 Claim, 7 Drawing Sheets
